UNITED STATES PATENT OFFICE.

HAMILTON HILDRETH WEBBER AND SAMUEL JACKSON BINGNER, OF MANSFIELD, OHIO.

SALES BOOK OR PAD.

SPECIFICATION forming part of Letters Patent No. 575,865, dated January 26, 1897.

Application filed March 19, 1893. Serial No. 583,996. (No model.)

To all whom it may concern:

Be it known that we, HAMILTON HILDRETH WEBBER and SAMUEL JACKSON BINGNER, residing at Mansfield, in the county of Rich- 5 land and State of Ohio, have invented a new and Improved Sales Book or Pad, of which the following is a specification.

This invention is an improved sales book or pad adapted for use in stores where a number of clerks are employed and a cash-carrier system in use. In such cases every purchaser receives a price-slip with the goods, and a 10 duplicate slip is forwarded by the clerk to the cashier.

Now the object of our invention is to provide a sales book or pad for the use of the clerk, and it is also the object of our invention to provide a book for this purpose which shall be cheaper and easier to manufacture 15 than those now in use, and one which is simpler, neater, and more convenient in use.

Another object is to provide a book or pad in which the carbon and protecting sheets can be arranged quicker than said parts in the books now in use, as it is a noticeable fact 20 that the average clerk takes as long to arrange the various slips as it takes to make the sale.

Another object of our invention is to guard 25 against mistakes by the salesman, as it frequently happens that the wrong slip is given to the purchaser, and this objection our invention entirely avoids by the means of different-colored slips for purchaser and cashier.

Another object of our invention is to provide 30 a book or pad in compact or block form in contradistinction to the long folded sheets now in common use.

Another object of our invention is to provide 35 means for holding the carbon and protecting sheets independent of the paper slips, and also holding them properly spaced with reference to the book or pad.

With these various objects in view and 40 such others as may hereinafter appear our invention consists in the peculiar construction of the various parts, and also in their novel combination or arrangement, all of 45 which will be fully described, and pointed out 50 out in the claims.

In the drawings forming a part of this speci-

fication, Figure 1 is a view showing the invention in use. Fig. 2 is a view showing the purchaser's slip detached and exposing the cashier's slip, the carbon-sheet being raised. 55 Fig. 3 is a view showing the cashier's slip detached, the carbon-sheet and one of the leaves being raised. Fig. 4 is a vertical longitudinal section.

In constructing a sales book or pad in accordance with our invention we employ a base or bottom piece A, of pasteboard or other material, and of the size and shape of the book or pad. A series of leaves B and B' are connected with this base at one end by means of 60 staples C, a suitable top piece or cross-strip C' being arranged at the edge of said leaves at their point of attachment.

The leaf B, intended to be delivered to the purchaser, is preferably made a different 65 color from the leaf B', which is intended to be delivered to the cashier, and these leaves are arranged alternately, as most clearly 70 shown, and in practice we make the leaf B yellow and the leaf B' pink, but it will of 75 course be understood that any colors can be used with exactly the same results. The leaves, furthermore, are made with a row of perforations D adjacent to the cross-strip C', so that said leaves are readily detachable, 80 the said cross-strip serving as a convenient edge to tear the leaves against.

At the opposite end of the base is arranged 85 a space-block E, of pasteboard, wood, or other material, said space-block being of a height equal to the thickness of the completed pad or book, and attached to said space-block is the protecting-sheet F, of waxed or oiled paper, and also the carbon-sheet G, the under 90 face of which carries the carbon. A cover H is also attached to this space-block, adapted to extend over the entire book or pad, thus completing the structure.

It is not at all necessary that the protecting-sheet F should be of waxed or oiled paper, 95 as ordinary paper would do as well, and, in fact, this sheet could be dispensed with entirely, if desired.

Whenever a sale is made, the clerk raises 100 the cover of the book or pad, and likewise the carbon and protecting sheets, and throws back a yellow and pink slip or leaf from the

opposite end. The protecting-sheet is then spread upon the exposed yellow slip or leaf. The pink slip or leaf, which is intended for the cashier, is then turned back upon the 5 protecting-sheet. The carbon-sheet is then spread out upon the pink slip and the yellow slip for the purchaser turned back over said carbon-sheet. The record of the sale is then written in pencil, and after the computation to has been made the purchaser's slip B is torn off, the carbon-sheet lifted, and the cashier's slip B' torn off and sent to the cashier's desk, if so desired, or the leaves B' could be left in the book or pad, but in practice it is preferred to detach them and forward to the 15 cashier. Thus in the drawings it will be seen that the entry of six yards of ribbon has been made, the cost of which is one dollar and fifty cents, and in Fig. 1 this is shown written 20 upon the slip B, which, as before stated, is torn off and delivered to the purchaser, and in Fig. 2 said slip is shown so detached, and also exposing the duplicate record upon the slip B', which is torn off and sent to the cashier. 25 By having the purchaser's and cashier's slips of different colors it will be impossible for the clerk to make a mistake, it being of course intended that the purchaser should receive the original entry, while the cashier will be sent 30 the carbon copy, or vice versa, if desired, but it will of course be understood that in either method uniformity will be required, and this we attain by preventing any possible mistake on the part of the clerk. 35 It will also be seen that all of the leaves are detachable at one end and at an opposite end from the carbon and protecting sheets, so that there is no danger of injuring said sheets by the rapid detachment of the leaves. 40 It will also be noticed that the carbon and protecting sheets are attached to a space-block which holds said sheets always at a

point slightly above the detachable leaves, so that there is no strain upon said leaves, and, furthermore, the insertion of said leaves can 45 be accomplished much quicker than by the method now in use. A cover II protects the entire book or pad against wear.

Having thus described our invention, what we claim as new, and desire to secure by Letters Patent, is—

1. An improved sales book or pad, comprising a base, a series of detachable leaves connected to the base at one end, the alternate leaves being of different colors, the space-block at the opposite end of the base, and the carbon and protecting sheets connected to the space-block, substantially as shown and described. 55

2. An improved sales book or pad, comprising a base, the cross-strip at one end of said base, a series of leaves detachably secured to the base, a space-block at the free end of such leaves, said space-block, cross-piece and leaves being of uniform thickness whereby to 60 produce a pad of regular or uniform thickness, the carbon the protecting-sheet and the cover secured to the upper face of the space-block all being arranged substantially as shown and for the purposes described. 70

3. An improved sales book or pad, comprising a base, a series of leaves attached thereto, each having a row of perforations near one edge, said leaves being of different colors and arranged alternately as described, the space-block at the opposite end of the base, the protecting-sheet, the carbon-sheet, and the top cover, all connected to said space-block, substantially as shown and described. 75
